MULTIPLE HAIR CURLER

Nathan L. Solomon, Mount Vernon, N. Y.

Application November 17, 1937, Serial No. 174,916

3 Claims. (Cl. 132—33)

The invention relates to a multiple hair curler. One of the objects of the invention is to construct a curler having a plurality of curling members which members are advantageously of different diameters so that different sized curls may be formed thereon. Another object of the invention is to utilize two curling members of the improved curler for the purpose of holding a normally closed bobbin in open position while a curl is being formed, the coacting curling members being so related that a formed curl may readily be transferred from the member on which it has been formed to the bobbin which functions to hold the curl in formation and in place.

The curler hereinafter described and claimed comprises a support, spaced curling members carried rotatably by the support, in combination, during the curling operation, with a hairpin, preferably of the bobpin type which pin has a spring action normally urging its legs or shanks into contact with each other, the legs being held spaced apart by the spaced curling members in which the legs of the bobpin are inserted.

The invention is illustrated by the drawing but it is to be understood that it is not limited to the form illustrated, modifications being apparent after a knowledge of the present disclosure.

In the drawing:

Fig. 1 is a perspective view of the curler, including a bobpin, this view showing the placement of loose ends of hair between a curling member and its clamp preparatory to the formation of a curl.

Fig. 2 is a perspective view of a formed curl which has been transferred from a curling member to a bobpin, the latter being shown in Fig. 1 in combination with the curling members.

Fig. 3 is a longitudinal sectional view of the curler.

Fig. 4 is a cross sectional view taken on the line 4—4 of Fig. 3.

Fig. 5 is a cross sectional view taken on the line 5—5 of Fig. 3; and

Fig. 6 is a view showing perspectively a group of elements associated in the curler.

Referring to the drawing for a more detailed description thereof, the numeral 1 indicates a support or holder for the curling members 8 and 9 which it supports rotatably in spaced relation. Said support or holder comprises complementary parts 1^a and 1^b which are clearly shown in Fig. 6 and therein shown as each having formed on its inner face a pair of semi-cylindrical bearings 1^c for the mentioned curling members. The parts 1^a and 1^b of the support are secured together by

a screw 10. The rotatable curling member 8 is prevented from moving longitudinally relative to the support, by the enlarged knurled head 8^a at one end of the bearing and the shoulder 8^b at the other end of the same, as clearly shown in Fig. 6, while the curling member 9 is held in place in its bearing due to its being reduced in diameter where it bears on its journal, as shown in Fig. 3. In other words, the support or strap 1 is arranged in the grooved portions 8^c and 9^d and interlocks therewith to prevent lengthwise displacement of the curlers.

The curling members 8 and 9 carry hair clamps 11 and 12 respectively, the clamps being pivoted intermediate the ends thereof on fulcrum pins 11^a and 12^a respectively, as shown in Fig. 3. Said clamps are alike, and comprise clamping portions proper 11^b and 12^b which fit into longitudinal grooves 8^e and 9^e respectively of the members 8 and 9 for the purpose of holding the free ends of hair while a curl is being formed. Said clamps 11 and 12 further include operating ends 11^c and 12^c respectively and said ends are respectively engaged and pressed upwardly by coiled springs 14 and 15 whereby the clamping portions proper 11^b and 12^b are normally pressed into the respective grooves 8^e and 9^e. To release the clamping ends it is only necessary to press down on the operating ends which, as shown in Fig. 1, project above the knurled head of the curling members 8^a and 9^a. The intermediate portions 11^d and 12^d of the mentioned clamps are deeper than their end portions for the purpose of rigidity and are positioned in slots 16 and 17 respectively which are continuous with other grooves mentioned 8^c and 9^c.

The spaced curling members 8 and 9 are bored an appreciable distance to receive, and hold spaced apart the legs of hairpin 18 which is a bobpin the legs of which are normally closed in contact.

As previously stated the members 8 and 9 are of substantially different diameters so that curls of different sizes may, selectively be formed on the curler. To form a curl, the clamping end of the clamp on the curling member selected is raised by depressing the operating end against the pressure of the associated spring, as shown in Fig. 1, the free ends of the hair to be curled being then inserted between the curling member and the clamping end of the clamp. Downward pressure on the operating end of the clamp is then released and the coiled spring closes the clamp so that the hair is secured to the curling member. The latter is then rotated to curl the

hair, by turning at its head. The curl being formed, and the bobpin being in the position shown in Fig. 1 and as described, the clamp is opened. Subsequently the curl is moved lengthwise off the curling member and as it is moved off, it pushes against the looped end of the bobpin and thus removes the pin from the curling members and the curl is thus transferred from the curling member on which it was formed to the bobpin one of the legs of which is inside the curl and the other of which is outside, as shown in Fig. 2, and since the legs of said pin are normally urged together, the legs of the pin coact to hold the curl formation.

I claim:

1. In combination, spaced tubes each having a reduced portion and spaced shoulders, each of said tubes having a slot disposed longitudinally thereof and interrupting said shoulders and extending along said reduced portions, said reduced portions having relatively deep recesses communicating with said slots, hair clamping means mounted on said tube and having relatively enlarged intermediately disposed depending portions movably fitting into said recesses and closely straddled by the walls thereof, means pivotally sustaining said depending portions, a strap comprising complementary members having mutually engaging inner surfaces and spaced grooves interrupting said surfaces, said grooves constituting spaced bearings rotatably guiding said reduced portions, manipulating means extending from said intermediately disposed portions, spring means cooperating with said manipulating means, said shoulders closely straddling the ends of said strap to prevent linear displacement of said tubes relative to said strap, and means for holding said complementary members in mutually engaging relation.

2. In combination, spaced tubes each having a reduced portion and spaced shoulders, each of said tubes having a slot disposed longitudinally thereof and interrupting said shoulders and extending along said reduced portions, said reduced portions having relatively deep recesses communicating with said slots, hair clamping means mounted on said tube and having relatively enlarged intermediately disposed depending portions movably fitting into said recesses and closely straddled by the walls thereof and hav- 50

ing notched portions above said depending portions, means pivotally sustaining said depending portions, a strap comprising complementary members having mutually engaging inner surfaces and spaced grooves interrupting said surfaces, said grooves constituting spaced bearings rotatably guiding said reduced portions, manipulating means extending from said depending portions, spring means cooperating with said manipulating means to hold said clamping means against said tubes, said shoulders closely straddling the ends of said strap to prevent linear displacement of said tubes relative to said strap, said strap fitting into said notched portions to prevent linear displacement of said clamping means relative to said tubes, and means for holding said complementary members in mutually engaging relation.

3. In combination, spaced tubes of different diameters and each having a reduced portion and spaced shoulders, each of said tubes having a slot disposed longitudinally thereof and interrupting said shoulders and extending along said reduced portions and said reduced portions having relatively deep recesses communicating with said slots, hair clamping means fitting into said interrupted shoulders and having relatively enlarged intermediately disposed depending portions movably fitting into said recesses and closely straddled by the walls thereof, means secured to said reduced portions for pivotally sustaining said depending portions, a strap comprising complementary members having mutually engaging inner surfaces and spaced grooves interrupting said surfaces, said grooves characterizing spaced bearings rotatably guiding said reduced portions, manipulating means extending from said depending portions, spring means within said tubes and cooperating with said manipulating means to hold said clamping means against said tubes, said shoulders closely straddling the ends of said strap to prevent linear displacement of said tubes, said clamping means having means interlocking with said strap to prevent displacement of said clamping means longitudinally of said tubes, and adjustable means common to said complementary members for holding the latter in mutually contacting relation.

NATHAN L. SOLOMON.
